(57) **CLAIM**

The ornamental design for a server door, as shown and described.

DESCRIPTION

FIG. 1 is a perspective view taken from the top and right side of a server door showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The server door is shown as used in the environment in FIG. 1 with the broken lines being shown for illustrative purposes only and form no part of the claimed design.
